UNITED STATES PATENT OFFICE

153,366

DESIGN FOR A FISHING PLUG RETRIEVER, OR SIMILAR ARTICLE

Franklin H. Kocarek, Chicago, Ill., assignor to
Peerless Tool & Engineering Co., Chicago, Ill.,
a corporation of Illinois

Application August 28, 1946, Serial No. 132,927

Term of patent 7 years

(Cl. D31—4)

To all whom it may concern:

Be it known that I, Franklin H. Kocarek, a citizen of the United States and a resident of the city of Chicago, in the county of Cook and State of Illinois, have invented a new, original, and ornamental Design for a Fishing Plug Retriever, or Similar Article, of which the following is a specification, reference being had to the accompanying drawing, forming a part thereof.

In the drawing:

Figure 1 is a plan view of a fishing plug retriever, or similar article, showing my new design;

Figure 2 is an elevational view; and

Figure 3 is another elevational view thereof.

I claim:

The ornamental design for a fishing plug retriever, or similar article, as shown.

FRANKLIN H. KOCAREK.
